UNITED STATES PATENT OFFICE

162,518

ELECTRIC RANGE SURFACE HEATING UNIT

Allan P. Charbonneau, Wauwatosa, Wis., assignor
to Cutler-Hammer, Inc., Milwaukee, Wis., a cor-
poration of Delaware

Application November 20, 1948, Serial No. 149,736

Term of patent 14 years

(Cl. D81—26)

To all whom it may concern:

Be it known that I, Allan P. Charbonneau, a citizen of the United States, and a resident of Wauwatosa, in the county of Milwaukee, and State of Wisconsin, have invented a new, original, and ornamental Design for an Electric Range Surface Heating Unit, of which the following is a specification, reference being had to the accompanying drawing, forming part thereof.

Figure 1 is a top plan view of an electric range surface heating unit incorporating my new design, and

Fig. 2 is a front elevational view thereof.

I claim:

The ornamental design for an electric range surface heating unit, substantially as shown.

ALLAN P. CHARBONNEAU.
